UNITED STATES PATENT OFFICE.

DELTA B. HOWELL, OF CHICAGO, ILLINOIS, ASSIGNOR OF ONE-HALF TO RAY Y. CLIFF,
OF SEBRING, OHIO.

SAGGAR.

1,384,468.

Specification of Letters Patent. Patented July 12, 1921.

Application filed March 26, 1920. Serial No. 368,849.

To all whom it may concern:

Be it known that I, DELTA B. HOWELL, a citizen of the United States, residing at Chicago, in the county of Cook and State of Illinois, have invented certain new and useful Improvements in Saggars, of which the following is a specification.

This invention relates to saggars such as are used in the manufacture of plates, saucers and other pottery or china ware, and the objects of the present invention are to provide an individual saggars in the form of a refractory ring for each plate or other similar article, the rings being placed one upon another to form tiers, suitable engaging means being provided for the rings of each tier in order to position the rings one upon another, certain of the rings being provided with interlocking means for engaging with corresponding rings in adjacent tiers in order to hold the tiers of saggars firmly together and prevent their falling over during the drying and burning operations, and as above stated are usually accomplished by a continuous movement of the trucks carrying the saggars through tunnel kilns.

The usual practice is to place the green ware in saggars usually made of considerable height so that a tier of dishes or the like can be placed in each saggars for drying and burning, the saggars containing the green ware being placed upon trucks for drying the ware and then placed in a kiln for burning the ware, the trucks carrying the saggars of dry ware being usually passed through a tunnel kiln for burning the ware.

In the drawings:

Figure 1 is a side elevation partly in section, showing how the saggars are assembled upon a truck;

Fig. 2, a plan view of the same;

Fig. 3, an enlarged plan view of one of the interlocking saggars;

Fig. 4, a section through the same;

Fig. 5, a plan view of one of the individual saggars;

Fig. 6, a plan view of a modified form of interlocking saggars;

Fig. 7, a section through the same;

Fig. 8, a plan view of another modified form of interlocking saggars; and

Fig. 9, a section through the same.

Similar numerals of reference indicate

corresponding parts throughout the drawings.

The individual saggars rings indicated by the numeral 1 are provided upon their upper faces with the concentric annular ribs 2 and upon their lower faces with corresponding annular grooves 3 the groove of each ring receiving the annular rib of the next lower ring in order to position the rings of each tier one upon the other.

Interlocking rings 4 such as are illustrated in detail in Figs. 3 and 4, are located at intervals in each tier, each of these interlocking rings being provided with the ribs 2 and the grooves 3 and with suitable interlocking means around its periphery such as the T-shaped lugs 5 and the corresponding T-shaped sockets 6 formed in peripheral lugs 7.

Each of the saggars rings is provided with the usual pins 8 which support the ware within the saggars in the usual manner. A plate or other similar article of green ware is placed in each of the rings and the rings are placed in tiers as shown in Figs. 1 and 2 the interlocking rings being located at suitable intervals in each tier and interlocked with the similar rings in adjacent tiers, thus positioning the rings of each tier one upon the other and connecting the several tiers together in a manner to prevent their falling over sidewise due to the movement of the trucks through the kilns.

In Figs. 6 and 7 is illustrated another form of interlocking means which may be provided upon the interlocking rings, the saggars rings 9 being provided with the peripheral lugs 10 having ribs 11 upon their upper faces and with lugs 12 having grooves 13 therein arranged to receive the ribs 11 of adjacent rings.

Still another form of interlocking means is illustrated in Figs. 8 and 9 in which each ring 14 is provided with the peripheral lugs 15 having projections 16 thereon arranged to engage the apertures 17 in the lugs 18 of adjacent rings.

In practice the saggars rings are stacked up in tiers as shown in Figs. 1 and 2 upon a truck 19, a plate or the like being independently supported within each ring. The engagement of the rings in each tier and the interlocking of rings of adjacent tiers effectively prevents side movement of any of the

racks and produces a structure of great stability and security.

A cap 20 may be placed upon the top saggar of each tier, as shown in Fig. 1.

- 5 Each of these caps is preferably provided with an annular groove 3^a in its lower surface, arranged to engage the annular rib 2 upon the top saggar.

I claim:

- 10 1. A saggar for holding articles to be fired, comprising a tier of superposed refractory rings, each adapted to support an article to be fired and engaging means upon certain of said rings for engaging corresponding rings in adjacent tiers.
- 15 2. A saggar for holding articles to be fired, comprising a plurality of tiers of superposed rings, each adapted to support an article to be fired and interlocking means upon certain rings of each tier arranged to engage corresponding rings in adjacent tiers.
- 20 3. A saggar for holding articles to be fired, comprising a plurality of tiers of superposed rings each adapted to support an article to be fired, engaging means upon the rings of each tier and interlocking means

upon certain rings of each tier arranged to engage corresponding rings in adjacent tiers.

4. A saggar for holding articles to be fired, comprising a plurality of tiers of superposed receptacles each adapted to support an article to be fired and interlocking means upon certain receptacles of each tier arranged to engage corresponding means on receptacles in adjacent tiers.

5. A saggar comprising a receptacle adapted to support an article to be fired and having interlocking means on the side for engaging corresponding means on like receptacles.

6. A saggar comprising a ring adapted to contain an article to be fired and having a rib upon its upper face and a corresponding groove upon its lower face and having a peripheral lug and a corresponding peripheral socket.

7. A saggar comprising a ring adapted to support an article to be fired and having a peripheral lug and a corresponding peripheral socket.

DELTA B. HOWELL.
